BOBBIN REPLENISHING MECHANISM
FOR LOOMS

Burt A. Peterson, Rockford, Ill., assignor to Barber-Colman Company, Rockford, Ill., a corporation of Illinois

Application December 16, 1947, Serial No. 791,960

28 Claims. (Cl. 139—245)

1

The invention pertains to a mechanism for delivering wound bobbins automatically to a weft replenishing loom, and has especial reference to a replenishing mechanism of the type in which the bobbins are individually supported upon carriers of the pin board type and transferred from such carriers automatically and successively to the loom shuttle.

Weft replenishing looms are commonly provided with means for supplying wound bobbins to the shuttle, such means including a rotary carrier or magazine containing a supply of wound bobbins, in combination with means responsive to the exhaustion of the bobbins in the operation of the loom to remove a wound bobbin from the magazine, deliver it to the shuttle and at the same time eject the exhausted bobbin from the shuttle.

One object of the present invention is to provide an improved mechanism for delivering wound bobbins to the rotary carrier or magazine permitting the use of bobbin carriers of the pin board type in which the individual holders are in the form of pins on which the bobbins are removably supported.

Another object is to provide an improved driving and control mechanism having a disengageable clutch connection with the loom drive under the control of the usual detector mechanism for the purpose of initiating successive bobbin replenishing cycles.

A further object is to provide in combination with the cycle initiating means aforesaid, means for effectually controlling the various operating parts of the mechanism and including in particular means operative in a plurality of successive cycles corresponding in number to the number of bobbins in each row of holders on the bobbin board to deliver such bobbins to the rotary carrier or magazine.

Still another object is to provide in a bobbin replenishing mechanism of the character above set forth, a bobbin rack having an initially retracted position with respect to the rotary magazine in which position it is adapted to receive a row of wound bobbins from a bobbin carrier such as a pin board, together with control means operative in each of a plurality of successive cycles to deliver bobbins to the magazine successively and in the last of such cycles to return the rack to its initial position for the reception of a new supply of bobbins.

A further object is to provide in a loom replenishing mechanism a bobbin loading rack for delivering wound bobbins to the rotary magazine

5 which rack is especially constructed for use with bobbin carriers of the pin board type and operative to disengage the bobbins from the individual holding pins and thence to move the bobbins successively into a predetermined loading position with respect to the magazines.

The objects of the invention thus generally set forth, together with other and ancillary advantages, are attained by the construction and arrangement shown by way of illustration in the accompanying drawings, in which:

10 Figure 1 is a fragmentary end elevational view of the weft replenishing side of a loom equipped with a bobbin supply and replenishing mechanism embodying my invention.

15 Fig. 2 is a fragmentary horizontal sectional view taken approximately in the plane of line 2—2 of Fig. 1 but on a larger scale.

20 Fig. 3 is a fragmentary section taken approximately in the plane of line 3—3 of Fig. 1 and also on a larger scale.

25 Fig. 4 is a similar view taken in the plane of line 4—4 of Fig. 1.

Fig. 5 is a fragmentary perspective view showing the construction of the loading rack and 30 showing especially the mounting of the bobbin holders thereof upon a slide shiftable transversely of the rack into position to receive a row of bobbins from the pin board and thence reversely to disengage the bobbins from the pin board.

35 Fig. 6 is a fragmentary perspective view illustrating the construction of the bobbin holders of the rotary magazine.

Fig. 7 is a fragmentary side elevational view 40 showing the cycling and control means, the supporting shafts being shown in section.

Fig. 8 is a fragmentary elevational view of a pin board indexing mechanism employed in the machine.

45 Fig. 9 is a schematic view in the form of a time chart showing the various operating cams and their relation to each other.

Referring to Fig. 1 of the drawings, I have shown for purposes of illustration a loom equipped 50 with a replenishing mechanism embodying my invention. This mechanism includes a rotary bobbin carrier or magazine 10 of the usual type having a plurality of peripherally spaced bobbin holders 11 for the reception of wound bobbins b. The magazine is mounted for rotation on a shaft 12 and bobbins supplied to the magazine are successively presented to a predetermined delivery position DP where they are operated upon by a conventional ejector 13 mounted upon an arm 14 which is pivoted on the loom frame. The arm 14

is arranged for actuation by the loom lay 15 under the control of a detector mechanism of conventional construction including a pivoted dog 16 responsive to the breakage or exhaustion of the thread. The lay 15 carries the usual bunter 17 with respect to which the dog 16 is pivoted. Upon exhaustion or breakage of the thread, the dog moves into blocking relation to the bunter for actuation thereby. As shown, the dog is pivotally supported upon an arm 18 rigid with a rockshaft 19 which in turn is journaled in a stationary frame member 20. The arm 18 is connected by a link 18a with the ejector arm 14 so that when the dog is positioned in the path of the bunter the latter is rendered effective to actuate the ejector arm 14. The bobbin ejecting means and its associated detector means cooperate to remove a spent bobbin from the shuttle and to transfer thereto a new bobbin from the magazine. Such means may therefore be said to constitute in general terms a bobbin change mechanism.

In accordance with my invention, wound bobbins are transferred from bobbin carriers C to the holders 11 of the magazine 10 by means of a reciprocating loading device in the form of a rack 21 having a series of bobbin receptacles or pockets 22. The rack is mounted for movement relative to the magazine on the one hand and the carriers C on the other so as to be capable of receiving a row of bobbins from a carrier and then present them successively to a loading position LP where they are engaged and held by the bobbin holders 11 of the magazine. The bobbin carriers C are preferably of the pin board type, providing a plurality of rows of pins 23 (Fig. 4), there being, as shown, five pins in each row. To support the pin boards, the frame of the machine is constructed to provide a slideway generally designated 24.

In the present embodiment of the invention, the rack 21 is mounted for movement radially of the magazine 10 and the slideway 24 is positioned so as to support the pin boards with the rows of bobbins on the pins 23 parallel with the rack at one side thereof. The pin boards are supported in a plane laterally offset (rearwardly as shown in Fig. 1) from the plane of the magazine and the rack is especially constructed so that when in its retracted position with respect to the magazine it is capable of being shifted transversely from its path of endwise reciprocation into position beneath the lowermost row of pins 23, and then, upon the advance of the lowermost row of pins into their respective receptacles 22, reversely so as to disengage the bobbins from the pins preliminary to the advance of the rack in carrying the bobbins successively into the loading position.

Having in view the general construction and arrangement thus described, the improved replenishing mechanism further comprises a driving and control mechanism initiated in operation in response to the breakage or exhaustion of the thread and operative in each of a plurality of successive cycles (corresponding in number to the number of bobbins in each row on the pin board) to advance a bobbin receptacle 22 on the rack 21 to the loading position LP and in the last or fifth of such cycles to return the rack to an initial or retracted position; and it further includes means operative to shift the rack transversely into position to receive a row of bobbins from a pinboard, index the pin boards to deliver bobbins to the rack and then shift the rack reversely to disengage the bobbins from their respective pins for subsequent transfer to the magazine.

Coming now to a more detailed consideration

of the construction employed in the present illustrative embodiment of the invention, the magazine 10 comprises a disk 26 having a series of equidistantly spaced radial arms 27 to each of which is secured a bobbin holder 11. As shown in Fig. 6, the latter is in the form of a U-shaped member 28 having opposed spring fingers 28 recessed at 30 to receive the conventional wire rings 31 (Fig. 4) on the butt ends of the bobbins. Thus the clips open radially outward so as to be capable of receiving the butt ends of the bobbin as the latter are moved radially inward by the rack 21.

Referring now to Figs. 1, 4 and 5, the rack 21 comprises a bar 32 carrying a plurality of blocks 33 coacting to form the bobbin receptacles or pockets 22 adapted to receive the butt ends of the bobbins b. The bar 32 forms the rear end member of a rectangular frame or cross slide 34 having side bars 35 and mounted on a longitudinal slide member 36. The latter is supported for movement radially of the magazine on a stationary frame bracket 37 constructed to provide ways 38 for the member 36. Rigid with the member 36 and perpendicular thereto are spaced parallel arms 39 providing ways 40 for the reception of the frame bars 35.

It will be seen that by this construction the rack 21 is mounted both for radial movement with respect to the magazine and also for movement from a position in which the pockets 22 are disposed in the plane of the magazine transversely into underlying relation to the lowermost row of bobbins supported on the pin boards C. In this position, the pockets 22 are adapted to receive the butt ends of the bobbins, and upon return into the plane of the magazine disengage the bobbins from the pins 23.

It will be observed from Fig. 5 that the blocks 33 which coact to form the bobbin pockets 22 are provided with recesses 41 shaped to hold the bobbins against axial movement in the pockets. To support the tip ends of the bobbins when thus resting in the pockets 22, the cross slide 34 further includes a front member 42 (Fig. 4) connecting the members 35 and provided with a notched angle plate 43 with notches 43a (Fig. 1) to receive the tips of the bobbins.

Referring now to Figs. 4 and 8, the slideway 24 for the bobbin board C comprises a pair of parallel bars 44 constructed to provide ways 45 for the edges of the pin boards C. These bars 44 are suitably mounted on the stationary frame 20 and are so positioned as to guide the pin boards in a direction perpendicular to the rack 21. The angle of the rack is so chosen that the slideway 24 is inclined from the horizontal sufficiently to cause the pin boards to move downwardly by the action of gravity.

The driving and control mechanism governing the replenishing operation comprises in the present embodiment of my invention a shaft 46 (Fig. 3) hereinafter termed the main cam shaft having an operating cycle timed with respect to the loom and serving principally to govern the indexing of the magazine 10. It has a disengageable driving connection with the loom shaft 47 (Fig. 1) effected by means including a clutch 48 (Figs. 2 and 3) operative in response to the breakage or exhaustion of the thread to initiate the operating cycle.

The driving and control mechanism further includes a shaft 49, hereinafter termed the auxiliary cam shaft, driven from the shaft 46 but at a reduced speed and having for its primary function the advance of the bobbin rack 21 from its initial

retracted position a plurality of steps toward the magazine 10, with a return to such initial position at the end of the last advancing movement. In the present instance the shaft 49 has a speed ratio of five to one with respect to the shaft 46 so that the shaft 49 rotates through one-fifth of a revolution for each complete revolution of the main cam shaft 46, it being observed that the five to one speed ratio is determined by the number of receptacles 22 in the rack 21.

The clutch 48 (Figs. 2 and 3) comprises in the present instance a shiftable clutch element 50 splined on the shaft 46, and a driven element 51 mounted for rotation relative to the shaft and herein rigid with a sprocket gear 52 journaled on the shaft and connected by a chain 53 with a sprocket gear 54 on the loom drive shaft 47. A stationary clutch element 55 rigid with a frame bracket 56 is engageable by the shiftable clutch element 50 upon disengagement from the driving element 51 so as to stop the shaft 46 in a predetermined position.

Engagement of the clutch to initiate an operating cycle in response to the breakage or exhaustion of the bobbin thread is effected by a clutch shifting mechanism arranged for actuation in one direction by the loom lay to effect engagement of the clutch, locked in clutch engaging position, and released for return and disengagement of the clutch after a predetermined operating cycle, herein one revolution of the main shaft 46. Said shifting mechanism comprises a bell crank 57 (Fig. 2) arranged for actuation in the present instance by a coiled spring 58 under the control of a shifter bar 59 operatively associated with the loom lay through the medium of the pivoted detector dog 16 mounted on the rockshaft 19 (Figs. 1 and 7). The bar 59 has a pin and slot connection 60 with an arm 61 rigid with the rockshaft 19 and is provided with a retracting spring 62. When the rockshaft 19 is operated by the laybunter 17 coating with the dog 16, the bar 59 is shifted in a direction (to the right, Figs. 2 and 7) to permit movement of the clutch shifting bell crank 57 by its spring 58. The bar 59 has a slot 63 therein for receiving one arm 64 of the bell crank 57 so that when the bar 59 is shifted to the right the bell crank is free to rock under the force of the spring 58, the slot 63 being of sufficient length to permit of a slight overtravel of the bar after engagement of the clutch for a purpose which will presently appear.

The latch means for holding the clutch engaged for a predetermined cycle of the main shaft 46 comprises in the present instance a latch member 65 (Fig. 7) engageable with a notch 66 in the upper edge of the bar 59. The latch 65 is fixed on a rockshaft 67 and urged by a coiled torsion spring 68 for movement into engagement with the notch. The latch 66 has a dog 69 thereon which rides upon the upper edge of the bar so as to enter the notch 65 as the bar is shifted in the operation of the rockshaft 19.

The clutch engaging movement of the bar occurs against the action of the retracting spring 62 which is made sufficiently stronger than the clutch spring 58 to be able to disengage the clutch upon release of the shifter bar by the latch 65. Such release of the latch occurs at the end of one revolution of the shaft 46 by the action of a cam 70 on the shaft 46 coating with a roller follower 71 on an arm 72 rigid with the latch member 65. It will be observed that after the bar 59 has been shifted in a direction to initiate an operating cycle and latched in this position, the arm 61 on

the rockshaft 19 is permitted to return with the return movement of the lay by reason of the pin and slot connection 60 between the arm 61 and the shifter bar 59.

The auxiliary cam shaft 49 is driven from the main cam shaft 46 through a gearing connection comprising a spur pinion 73 (Figs. 1 and 3) on the main cam shaft meshing with a spur gear 74 fast on the auxiliary cam shaft 49. As shown (Fig. 3) the gear 74 is mounted upon the hub of a barrel cam 75 which is keyed to the shaft 49. The barrel cam is keyed to the shaft 49 and is pinned together with a disk cam 16 to the spur gear 74.

The barrel cam 75 forms a part of a mechanism for actuating a thread end finder as will presently be described, and the cam 76 serves to control the advancing and retracting movements of the bobbin rack 21. As shown in Fig. 7, this latter cam acts to shift the rack 21 by means of a gear segment 77 mounted on a rockshaft 78 upon which is secured a second arm 79 carrying a roller follower 80 for coaction with the cam. The shaft 78 is mounted on the frame bracket 81, and a coiled torsion spring 82 acting between this bracket and the shaft tends to hold the roller follower 80 against the cam. The segment 77 meshes with a rack bar 83 rigid with the longitudinal side bar 36 (Fig. 3), and the arrangement is such that in the rotation of the cam 76 in a counterclockwise direction (Fig. 7) the rack 21 is advanced with a step-by-step motion through five successive steps and then returned by the spring 82 under the control of the cam into its retracted position with respect to the magazine.

As shown in Fig. 7, the cam 76 is divided into five equal segments. Four of the segments provide dwell surfaces 84, 84a, 84b and 84c followed respectively by relatively short rising surfaces 85, 85a, 85b and 85c. The fifth segment provides a short dwell surface 86, a relatively steep slope 86a, a dwell surface 86b and a rising cam surface 86c. For each revolution of the main cam shaft 46, and therefore once in each cycle of the replenishing mechanism, the cam 76 is rotated through one-fifth of a revolution, and in each cycle the rack is advanced a distance corresponding to the pitch of the bobbin receptacles 22 of the rack 21. At the beginning of the fifth cycle, the rack dwells momentarily while the magazine is indexed as hereinafter set forth, and then permitted to return to its initial position by the action of the spring 82.

Upon such return of the rack to its initial position, the cross slide 34 is actuated to effect the transfer of the lowermost row of bobbins from the lowermost pin board to the bobbin receptacles 22 of the rack. This is accomplished by means of a cam 87 (Fig. 7) fast on the main cam shaft 46 and acting upon a roller follower 88 carried by a rocker arm 89 which is connected by means of a link 90 with a bell crank 91 (Fig. 3) operatively associated with the cross slide 34. The bell crank 91 is mounted on a rockshaft 92 suitably supported on a frame bracket 93 and is urged by a torsion spring 93a in a direction to hold the follower 88 against the cam 87. The bell crank has one arm 94 connected with the link 90 and two arms 94a (see Fig. 1) formed with notches 95 in their free ends for coaction with two lugs 96 rigid with the cross slide. Notwithstanding the fact that the cam 87 is on the main cam shaft 46 and therefore serves to actuate the bell crank 91 once in each operating cycle, the cross slide 34 is nevertheless actuated only in one of these cycles, namely, in the last of the five cycles above

mentioned following the return of the rack to its initial retracted position. This is for the reason that the lugs 96 are of such length as to be received in the notches 95 of the bell crank arms 94a only when the rack occupies its retracted position. In all other operations of the bell crank, the lugs 96 are disengaged from the arms 94a so that the bell crank is ineffective, operating through idle strokes. In any case, the timing of the operation of the bell crank is such as to occur at the time that the rack 21 is stationary due to the engagement of the roller follower 88 with one of the dwell surfaces, the dwell being of sufficient length to provide for the transverse shifting movement of the rack, the indexing of the bobbin carriers (to be described presently) and the reverse movement of the cross slide, in which latter movement the lowermost row of bobbins is disengaged from their respective pins 23 on the bobbin carriers or pin boards C.

The cross slide 34 is yieldably held in the position shown in Fig. 4 in which the bobbin pockets are aligned with the magazine. For this purpose, one of the way members 39 for the cross slide is formed with a slot 97 for the reception of a pivoted dog 98 yieldably held by a spring 99 in engagement with a notch 100 in the adjacent frame member 35 of the cross slide. The edge of the notches 100 are inclined so as to permit the dog to yield with a cam action when positively moved by the cam 87.

Referring now to Fig. 8, means is provided for controlling the indexing of the pin boards C in their slideway 24. As above indicated, the slideway is inclined sufficiently to cause the pin boards to descend therein by the action of gravity. Accordingly, the indexing control operates in the nature of an escapement. As shown, it comprises two diametrically opposed detent fingers 101 and 102 pivotally mounted in a suitable recess in one of the frame members 44 and engageable with notches 103 in one edge of each board. For convenience the finger 101 may be termed the releasing finger and the finger 102 the positioning finger.

The releasing finger 101 is arranged for cam actuation and the positioning finger 102 has a one-way connection with the finger 101 for withdrawal thereby but is independently movable into active position. Thus the finger 101 carries a pin 104 engaging with a lug 105 rigid with the finger 102 and the finger 102 is urged by a leaf spring 107 in the direction of the pin board. The finger 101 is connected by a link 108 to one arm 109 of a bell crank 110 having a second arm 111 equipped with a roller follower engaging a cam 112 on the auxiliary cam shaft 49. The operation is as follows:

When the bobbin rack 21 has been shifted transversely by its cam 87 into position beneath the lowermost row of bobbins, a recess 112a in the cam 112 permits movement of the bell crank 110 by a spring 113, forcing the releasing finger 101 inwardly into an awaiting notch 103 and simultaneously withdrawing the positioning finger 102 from another notch 103. The width of the notches 103 is somewhat greater than the corresponding width of the end portion 101a of the finger 101 so that immediately upon the release of a pin board by the finger 102 the pin board will advance a distance sufficient to carry the notch then opposite the finger 102 beyond the latter. As a result, the finger 102 will engage with the edge of the pin board so as to ride thereon in the ensuing indexing movement of

the board incident to the withdrawal of the finger 101 by the cam 112. It will be observed that when the finger 101 is then withdrawn the finger 102 is urged by its spring 107 against the pin board so as to enter the next notch 103 and thus interrupt the downward movement of the board to complete the indexing operation.

Upon the delivery of the lowermost row of bobbins to the rack 21, the cam 87 operates upon the bell crank 110 to return the rack into the plane of the magazine, and in the ensuing cycle of the main cam shaft the rack is advanced one step by the cam 76 to deliver the first of the bobbins in the lowermost row to an awaiting holder 11 of the magazine 10.

It will be understood that the magazine 10 is indexed in timed relation to the movements of the rack 21 for the purpose of removing bobbins from the rack and carrying wound bobbins into the delivery position DP. Such indexing movements of the magazine 10 occur at the beginning of each cycle of the main cam shaft 46 and is accomplished in the present instance by an intermittent gear drive (Fig. 7) comprising a toothed gear 114 fast on the shaft 46 and a notched gear 115 fast on the magazine shaft 12.

After the movement of a bobbin into the delivery position, the end of the thread on the bobbin is seized and held by an end finder 116. As shown in Fig. 2 of the drawings, this finder comprises a sleeve 117 mounted upon a rod 118 suitably supported on the machine frame. At the forward end of the sleeve in laterally offset relation thereto is a finder tube 119. The tube is supported on an arm 120 rigid with the sleeve and carries a plurality of spring fingers 119a operative when the tube is moved axially over the tip end of the bobbin b to seize the end finder coil b' thereof and to withdraw it from the bobbin. The means for actuating the sleeve 117 comprises an arm 121 having a pin and slot connection 122 with the sleeve 117 and arranged for actuation by the barrel cam 75. The arm 121 is pivoted between its ends on a pivot pin 123 carried by a bracket 124, and the end of the arm opposite the sleeve carries a roller follower 125 for engagement with the cam 75. The latter being mounted upon the auxiliary cam shaft 49 as above described, has a series of circumferentially spaced cam lobes 126 one of which is operated in each cycle of the main cam shaft to swing the arm 121 against the action of a coiled torsion spring 127 so as to cause the finder tube 119 to move into engagement with the tip end of the bobbin b and then reversely so as to withdraw and hold the end finding coil b'.

The return movement of the sleeve 117 occurs at a point in the loom cycle in which the lay 15 is commencing its return stroke. To insure that the bobbin thread held by the finder tube will be effectually threaded on the eye of the shuttle moving with the lay, means is provided to impart a slight rotational movement to the sleeve and therefore a lateral movement to the finder tube 119, after disengagement of the tube from the bobbin, so that the movement of the tube will follow the lay. The means provided for this purpose consists of a pin 128 carried by the sleeve 117 and projecting into a cam groove 129 in the supporting rod 118. The cam is so shaped that after the initial portion of the movement of the arm 121 (see broken lines in Fig. 2) a rotational movement is imparted to the sleeve 117 in the direction of movement of the lay.

The operation may now be summarized, having reference to the time chart shown in Fig. 9, wherein the various operations are related to the main cam shaft cycle.

Assuming that the bobbin rack 21 has been advanced through its full range of movement so that the uppermost pocket 22 occupies the loading position LP and further assuming that the loom detector mechanism has detected the exhaustion of the bobbin in the shuttle, the sequence of operation is as follows: The pivoted dog 16 disposed in the path of the bunter 17 in response to thread exhaustion is engaged by the bunter in the advance of the lay so as to cause engagement of the clutch 48 through the operation of the clutch shifting bar 59 (Fig. 7). Upon such actuation of the bar, the latch 65 becomes effective to hold the bar and therefore the clutch in its engaged position with the result that the cam shafts 46 and 49 are set in motion.

In the initial portion of the cycle (twenty degrees of rotation) while the roller follower 80 is in engagement with the dwell surface 86 of the cam 76, an indexing motion is imparted to the magazine by the intermittent gearing 114, 115 to carry a filled bobbin into the delivery position DP. Thereupon, the cam 76 effects the return of the bobbin rack 21 to its initial retracted position. This occurs as shown in the time chart in the next one hundred seventy-five degrees of rotation of the main cam shaft during which the roller follower 80 coacting with the sloping cam surface 86a permits movement of the rack 72 by its spring 82 in a direction and to the extent necessary to return the rack to its initial position. At the end of the return stroke, the follower engages with a short dwell surface 86b, herein of a length corresponding to seventy degrees of rotation of the main cam shaft.

While the rack 21 dwells in its returned position, the cam 87 becomes effective to reciprocate the cross slide 34. In this operation, the roller follower 88 is urged by the bell crank spring 93a into the recess 87a of cam 87 so as to impart to the slide a short transverse movement sufficient to carry it from the plane of the magazine laterally into position beneath the lowermost row of bobbins on the pin board. The cam is rendered effective to cause such shifting movement of the cross slide due to the fact that in the retracted position of the rack the lugs 96 thereon are received within the notched ends of the bell crank arms 94a.

The shape of the recess 87a is such as to cause the cross slide to dwell momentarily in its shifted position, this dwell occurring during a twenty-five degree rotation of the main cam shaft. During such dwell, the bobbin board index cam 112 (Fig. 8) becomes effective to cause the advance of the bobbin board one step or sufficient to carry the lowermost row of bobbins into the awaiting pockets 22 of the rack 21. In this operation, the roller follower on the bell crank 110 enters the recess 112a of the cam 112, rendering the spring 113 effective to cause engagement of the releasing finger 101a and disengagement of the positioning finger 102 with respect to the recesses 103 in the bobbin board. Immediately thereafter, the finger 101a is withdrawn and the finger 102 becomes effective to control the length of the indexing movement. The cross slide cam 87 thereupon becomes effective to return the cross slide and therefore the rack 21, disengaging the bobbins from their respective pins on the pin 75

board and positioning the rack in alignment with the magazine.

The transverse shift of the cross slide having occurred while the roller follower 80 engages the dwell surface 86b of the cam 76, the bobbin rack cam 76 now becomes effective near the end of this cycle to advance the rack 21 one step. This occurs as the roller follower 80 is engaged by the rising cam surface 86c, the follower coming to rest upon the following dwell surface 84 of the cam. As shown in the time chart, such advancing movement of the rack commences at two hundred sixty-five degrees and terminates at three hundred sixty degrees.

10 The cycle is terminated by the latch cam 78 acting upon the latch 65 to disengage it from the clutch shifter bar 59. The bar is thus released to the action of its spring 62 so as to effect disengagement of the clutch sleeve 50 from the driving element 51 and engagement of such sleeve with the stationary element 55, thereby bringing the mechanism to rest.

15 In the four succeeding cycles of the replenishing mechanism, the operation is repeated except that the cam 87 is rendered ineffective to actuate the cross slide, due to the fact that the lugs 96 on the slide have been moved out of alignment with the notched arms 94a. In each of such stepping movements, the rack is advanced after a preliminary dwell by the coaction of the roller follower 80 with one of the cam surfaces 85. The rising cam surfaces 85, 85a, 85b and 85c are somewhat steeper than the surface 86c so that each of the four successive advancing movements occur as shown in the time chart in the rotation of the main cam shaft from three hundred five degrees to three hundred sixty degrees. Following each advance and throughout the remainder of the cycle of the main cam shaft, the rack is held 20 stationary.

25 During each of the five cycles, the end finder cam 75 operates to shift the end finder tube 118 axially over the tip end of the bobbin in the delivery position and then reversely so as to remove 30 from the tip end of the bobbin the end finder coil b'. After disengagement of the tube from the bobbin, a slight rotational movement is imparted to the supporting sleeve 117 so as to cause the tube to move laterally and follow the movement of the lay which at this time has commenced its return stroke.

35 I claim as my invention:

40 1. In a bobbin replenishing mechanism for looms having a drive shaft and a detector mechanism responsive to the exhaustion of the shuttle bobbin, the combination of a rotatable magazine having a circumferential series of bobbin holders thereon, a reciprocating loading device having a series of bobbin receptacles, and a driving and control mechanism for indexing said magazine step-by-step and for advancing said loading device to deliver bobbins one-by-one to said magazine, said driving and control mechanism comprising a driven shaft having a disengageable clutch connection with said loom shaft, means controlled by said detector mechanism for engaging said clutch, and means on said shaft for effecting the disengagement of said clutch.

45 2. In a bobbin replenishing mechanism for looms having a drive shaft, the combination of a rotatable magazine having a circumferential series of bobbin holders thereon and movable step-by-step to carry said holders into and out of a predetermined loading position successively, 50 a reciprocating loading device having a series

11

of bobbin receptacles supporting a row of bobbins, and a driving and control mechanism for effecting the advance of said loading device step-by-step and to carry said bobbins one-by-one to said loading position and for returning said device to its initial position following delivery of the last bobbin in the row to the magazine, said driving and control mechanism having a disengageable clutch connection with said loom shaft.

3. In a bobbin replenishing mechanism for looms having a drive shaft and a shuttle change mechanism, the combination of a rotatable magazine having a circumferential series of bobbin holders thereon, a reciprocatory loading device having a series of bobbin receptacles, and a driving and control mechanism for indexing said magazine, advancing said loading device to deliver bobbins one-by-one to the magazine and returning the loading device to an initial retracted position, said driving and control mechanism comprising a driven shaft, means including a clutch for connecting the driven shaft with the loom shaft and means controlled by said shuttle change mechanism for causing engagement of said clutch to initiate the operation of said driven shaft.

4. In a bobbin replenishing mechanism for looms having a drive shaft and a shuttle change mechanism, the combination of a rotatable magazine having a circumferential series of bobbin holders thereon, a reciprocatory loading device having a series of bobbin receptacles, and a driving and control mechanism for indexing said magazine, advancing said loading device to deliver bobbins one-by-one to the magazine and returning the loading device to an initial retracted position, comprising a cam shaft, a clutch connecting said cam shaft with the loom shaft and means controlled by the shuttle change mechanism for engaging said clutch to initiate a cycle of operation of the cam shaft, said cam shaft having an intermittent driving connection with said magazine.

5. In a bobbin replenishing mechanism for looms having a drive shaft and a shuttle change mechanism, the combination of a rotatable magazine having a circumferential series of bobbin holders thereon, a reciprocatory loading device having a series of bobbin receptacles, and a driving and control mechanism for indexing said magazine, advancing said loading device to deliver bobbins one-by-one to the magazine and returning the loading device to an initial retracted position, comprising a driven shaft having an intermittent driving connection with the magazine, means controlled by the shuttle change mechanism to initiate a cycle of operation of the driven shaft, and a cam shaft having a cam thereon operative in successive cycles of the driven shaft to impart successive advancing movements to said loading device, said cam being further operative in one of said cycles to effect the return of said device to its initial position.

6. In a bobbin replenishing mechanism for looms having a power driven shaft and a shuttle change mechanism, the combination of a rotatable magazine having a circumferential series of bobbin holders thereon, a loading device having a series of bobbin receptacles, and a driving and control mechanism for indexing said magazine and actuating said loading device in timed relation to the movements of the magazine, said driving and control mechanism comprising a driven shaft, means connecting said shaft to the loom

shaft including a clutch, clutch engaging means arranged for actuation by the loom drive shaft under the control of said shuttle change mechanism, and means operative at a predetermined point in the rotation of the driven shaft for disengaging said clutch.

7. In a bobbin replenishing mechanism for looms having a power driven shaft and a shuttle change mechanism, the combination of a rotatable magazine having a circumferential series of bobbin holders thereon, a loading device having a series of bobbin receptacles and a driving and control mechanism for indexing said magazine and actuating said loading device in timed relation to the movements of the magazine, said driving and control mechanism comprising a driven shaft, means connecting said shaft to the loom shaft including a clutch, a clutch shifting member arranged for actuation by the loom shaft under the control of said shuttle change mechanism to initiate a cycle of operation of said driven shaft, and latch means for holding said clutch engaged.

8. In a bobbin replenishing mechanism for looms having a power driven shaft and a shuttle change mechanism, the combination of a rotatable magazine having a circumferential series of bobbin holders thereon, a loading device having a series of bobbin receptacles and a driving and control mechanism for indexing said magazine and actuating said loading device in timed relation to the movements of the magazine, said driving and control mechanism comprising a driven shaft, means connecting said shaft to the loom shaft including a clutch, a clutch shifting member arranged for actuation by the loom shaft under the control of said shuttle change mechanism to initiate a cycle of operation of said driven shaft, latch means for holding said clutch engaged, and means operative at a predetermined point in the rotation of said driven shaft for disengaging said latch means to cause disengagement of said clutch.

9. In a bobbin replenishing mechanism for looms having a power driven shaft and a shuttle change mechanism, the combination of a rotatable magazine having a circumferential series of bobbin holders thereon, a loading device having a series of bobbin receptacles, and a driving and control mechanism for indexing said magazine and actuating said loading device in timed relation to the movements of the magazine, said driving and control mechanism comprising a driven shaft, means connecting said driven shaft to the loom shaft including a clutch, a clutch shifting member arranged for actuation by the loom drive shaft under the control of said shuttle change mechanism, said clutch shifting member being operative upon actuation to render said spring means effective to engage said clutch, and means operative after a predetermined cycle of rotation of the driven shaft to effect a reverse shifting movement of said member to disengage said clutch and terminate said cycle.

10. In a bobbin replenishing mechanism for looms having a power driven shaft and a shuttle change mechanism, the combination of a rotatable magazine having a circumferential series of bobbin holders thereon, a loading device having a series of bobbin receptacles and a driving and control mechanism for indexing said magazine and actuating said loading device in timed relation to the movements of the magazine, said driving and control mechanism comprising a

driven shaft, means connecting said driven shaft to the loom shaft including a clutch, spring means tending to engage said clutch, a clutch shifting member arranged for actuation by the loom drive shaft under the control of said shuttle change mechanism, said clutch shifting member being operative upon actuation to render said spring means effective to engage the clutch, other spring means energized in the clutch engaging movement of the shifting member, latch means operative upon said shifting member to hold the shaft in engaged position, and means operative at a predetermined point in the rotation of the driven shaft for disengaging said latch means so as to render said other spring means effective to disengage the clutch against the action of the first mentioned spring means.

11. In a bobbin replenishing mechanism for looms having a power driven shaft and a shuttle change mechanism, the combination of a rotatable magazine having a circumferential series of bobbin holders thereon, a reciprocatory loading device having a series of bobbin receptacles, and a driving and control mechanism for indexing said magazine, advancing said loading device to deliver bobbins one-by-one to the magazine and for returning the loading device to an initial retracted position, said driving and control mechanism comprising a driven shaft arranged for actuation by the loom shaft through a predetermined operating cycle under the control of said shuttle change mechanism and cam means governing the stepping and return movements of said loading device, said cam means being operative to impart successive advancing movements to the loading device in a predetermined number of successive cycles of the driven shaft and to return the device to an initial retracted position in the last of said cycles.

12. In a bobbin replenishing mechanism for looms having a power driven shaft and a shuttle change mechanism, the combination of a rotatable magazine having a circumferential series of bobbin holders thereon, a reciprocatory loading device having a series of bobbin receptacles, and a driving and control mechanism for indexing said magazine, advancing said loading device to deliver bobbins one-by-one to the magazine and for returning the loading device to an initial retracted position, said driving and control mechanism comprising a main shaft arranged for actuation by the loom shaft through a predetermined operating cycle under the control of said shuttle change mechanism, a cam shaft driven from said main shaft at a reduced speed such that for each revolution of the cam shaft the main shaft is rotated through a plurality of revolutions corresponding in number to the number of receptacles in said loading device, and a multilobed cam on said cam shaft operative to impart one stepping movement to the loading device for each cycle of rotation of the main shaft and to return the device to its retracted position in the last of said cycles.

13. A bobbin replenishing mechanism for looms having, in combination, a rotary magazine with a plurality of bobbin holders adapted to receive and support wound bobbins in a predetermined loading position and move the same out of such position, a loading rack mounted for movement radially of said magazine at said loading position and having a series of laterally opening receptacles releasably supporting a row of bobbins, means for imparting stepping movements to the rack and for returning the rack following the

5 delivery of the last bobbin in the row to the magazine, and means operative automatically upon the return of the rack to its initial position to supply a new row of bobbins to the rack comprising a support for a bobbin carrier having a row of pins for releasably holding a row of bobbins, said supporting means being positioned with respect to the magazine to support the carrier in a plane offset laterally with respect to the magazine, means for indexing the bobbin carrier, and means operative in timed relation to said indexing means to impart a transverse shifting movement to the rack to position it for the reception of a row of bobbins preliminary to an indexing 10 movement of the carrier and then return the rack to disengage the bobbins from their respective pins and to position them for delivery to the magazine.

14. In a bobbin replenishing mechanism for 20 looms, a loading rack having a series of receptacles for receiving and retaining a row of bobbins, means for supporting said rack for reciprocation in a predetermined path, means for advancing said rack to carry the bobbins one-by-one into a predetermined loading position and thereafter return the rack to its initial position, means for supporting a bobbin carrier having a row of bobbin supporting pins with said row disposed parallel to said rack when the latter is in its initial position and at one side thereof, and means operative upon the rack when in its retracted position to shift the same laterally of said path into position to receive a row of bobbins on said carrier pins and then reversely into said 30 path, said bobbin receptacles engaging with bobbins on said pins in such reverse movement of the rack to disengage the bobbins from the pins.

15. In a bobbin replenishing mechanism for 40 looms, a rotary magazine having a plurality of bobbin holders thereon, a loading rack having a series of receptacles for receiving and retaining a row of bobbins, means supporting said rack for movement in a predetermined path radially of said magazine, said rack having an initially retracted position with respect to the magazine, means for supporting a pin board having a row of bobbin supporting pins thereon corresponding in number to the receptacles in said rack and disposed parallel to the rack laterally of said path, means for shifting said rack laterally of said path and into position to receive a row of bobbins supported on said pins and then reversely to disengage the bobbins from the pins, means operative following such reverse movement 50 of the rack to advance the rack step-by-step to deliver the bobbins one-by-one to the magazine, and means for indexing the magazine in timed relation to the advance of the rack.

16. In a bobbin replenishing mechanism for 60 looms, a rotary magazine having a series of bobbin holders thereon, a loading rack having a series of bobbin receptacles thereon, means supporting said rack for movement radially of the magazine and also transversely thereof, said rack having an initial retracted position relative to the magazine, means for imparting a transverse shifting movement to the rack when in retracted position and then reversely into its said initial position, means operative upon such transverse shifting of the rack to deliver thereto a row of bobbins, and means for indexing said rack and said magazine in timed relation to each other so as to deliver bobbins one-by-one to said magazine.

17. In a bobbin replenishing mechanism for 70 looms, a rotary magazine having a series of

bobbin holders thereon, a loading rack having a series of bobbin receptacles, means supporting said rack for movement in a predetermined path radially of the magazine and also for movement laterally of said path when in a predetermined retracted position with respect to the magazine, means operative when the rack is in its said retracted position to shift the same laterally and then reversely into said predetermined path, means operative while the rack is in such laterally shifted position to deliver thereto a row of bobbins, said rack receptacles being adapted to engage the bobbins so that upon the reverse shifting movement thereof the bobbins are carried with the rack, means for advancing the rack step-by-step to deliver bobbins one-by-one to the magazine and then returning the rack to its said retracted position, and means for indexing the magazine in timed relation to the stepping movements of the rack.

18. In a bobbin replenishing mechanism for looms, a loading rack having a series of receptacles for receiving and retaining a row of bobbins, means supporting said rack for reciprocation along a predetermined path and also laterally thereof when the rack is in a predetermined position, said supporting means for the rack comprising a member movable parallel to said path and a cross slide on said member, cam means for actuating said cross slide to shift the rack laterally of said path and then to return it to said path, means operative in the shifted position of the rack to deliver a row of bobbins to the rack, and means for advancing the rack step-by-step to carry said bobbins one-by-one into a predetermined loading position.

19. In a bobbin replenishing mechanism for looms having a power driven shaft and a shuttle change mechanism, a rotary magazine having a series of bobbin holders thereon, a bobbin loading rack having a series of bobbin receptacles for receiving and retaining a row of bobbins, means for supporting said rack for movement radially of the magazine and also laterally into a bobbin receiving position at one side of said path, means operative when the rack is in said receiving position to deliver a row of bobbins to said receptacles, and a driving and control mechanism including means for indexing said magazine, reciprocating said rack transversely of said path and for advancing said rack step-by-step in timed relation to the indexing of the magazine, said means including a driven shaft, means controlled by said shuttle change mechanism to initiate a cycle of operation of the driven shaft and cam means on the driven shaft for shifting the rack laterally, said cam means being operative only in the retracted position of the rack.

20. In a bobbin replenishing mechanism for looms, a loading rack having a series of bobbin receptacles, a support mounted for reciprocation along a predetermined path, a cross slide carrying said rack and mounted for movement on said support transversely of said path, cam means for imparting step-by-step advancing movements to said support and then returning the support to an initial retracted position, means for reciprocating said cross slide transversely of said path to carry said rack into a bobbin receiving position and then reversely into said path comprising a reciprocating actuator and means providing a disengageable connection between said actuator and said cross slide effective only when the rack occupies said predetermined retracted posi-

tion, the cam means for actuating the support and for reciprocating the cross slide being timed so that said connection is established as an incident to the return of the support to its said initial position.

5 21. In a bobbin replenishing mechanism for looms, a loading rack having a series of receptacles for receiving a row of bobbins, a support mounted for reciprocation along a predetermined path, a cross slide supporting said rack and mounted on said support for movement transversely thereof, a reciprocating actuator, and means on said cross slide operative only in a predetermined position of the rack to provide a connection with said actuator.

10 22. In a bobbin replenishing mechanism for looms, a slideway for a bobbin carrier having a plurality of recesses uniformly spaced apart in the direction of movement of the carrier on the slideway, an indexing mechanism comprising releasing and positioning fingers respectively engageable in said recesses, power operated means for moving said releasing finger into engagement with one recess and then withdrawing it therefrom, spring means acting on the positioning finger tending to move it into engagement with another one of said recesses, and a one-way connection between said fingers operative in the movement of the releasing finger into engagement with its said recess to disengage the positioning finger from its recess, said releasing finger being dimensioned with respect to said recesses so as to permit movement of the bobbin carrier while the releasing finger is in engagement with its recess sufficient to prevent entry of the positioning finger into its recess under the influence of its spring upon the withdrawal of the releasing finger from its said recess.

20 23. In a bobbin replenishing mechanism for looms, a slideway for a bobbin carrier having a plurality of recesses uniformly spaced apart in the direction of movement of the carrier on the slideway, and means for indexing the bobbin carrier comprising releasing and positioning fingers respectively engageable in spaced recesses, a one-way connection between said fingers, power operated means for moving said fingers conjointly but in opposite directions, and spring means for moving the positioning finger independently so as to render it effective to engage and position the bobbin carrier following release by the releasing finger.

25 24. In a bobbin replenishing mechanism for looms, a slideway for a bobbin carrier having a plurality of recesses uniformly spaced apart in the direction of movement of the carrier on the slideway, and means for indexing the bobbin carrier comprising a positioning finger spring pressed for movement into one of said recesses, a releasing finger engageable with another one of the recesses, power operated cam means for actuating the releasing finger into and out of engagement with its recess, and means operative in the engaging movement only of the releasing finger to withdraw the positioning finger from its recess.

30 25. In a bobbin replenishing mechanism for looms having a reciprocating lay with a shuttle box thereon, a rotary magazine having a circumferential series of bobbin holders, means for indexing said magazine step-by-step to carry bobbins successively into a predetermined delivery position for transfer to the shuttle box, an end finder mounted for movement axially of a bobbin in said delivery position and operative to seize an end finding coil on the bobbin and to

withdraw it therefrom, means for reciprocating said finder, and means operative in the withdrawal movement of the finder to impart a lateral shifting movement thereto, said reciprocating means being arranged for actuation in timed relation to the loom whereby the withdrawal movement of the finder occurs in the return movement of the loom lay.

26. In a bobbin replenishing mechanism for looms having a reciprocable lay, a rotary magazine having a series of bobbin holders thereon, means for indexing the magazine to carry said bobbins successively into a predetermined delivery position, an end finder having means for engaging with the tip end of a bobbin in said delivery position to seize an end finding coil thereon, a reciprocable support for said finder, power driven means for reciprocating said support to move the finder into and out of engagement with a bobbin in the delivery position, and means operative as an incident to the withdrawing movement of the finder to impart a lateral shifting movement thereto in the direction of return movement of the loom lay.

27. In a bobbin replenishing mechanism for looms, a rotary magazine having a series of bobbin holders thereon, means for indexing the magazine to carry said bobbins successively into a predetermined delivery position, an end finder having means for engagement with a tip end of a bobbin in said delivery position to seize an end finding coil thereon, a reciprocable and rotatable support having said finder mounted eccentrically thereof, power driven means for reciprocating said support to move the finder into and out of engagement with a bobbin in the delivery posi-

tion, and means operative as an incident to the withdrawing movement of the finder to impart a lateral shifting movement thereto.

28. In a bobbin replenishing mechanism for looms, a rotary magazine having a series of bobbin holders thereon, means for indexing the magazine to carry said bobbins successively into a predetermined delivery position, an end finder having means for engagement with a tip end of a bobbin in said delivery position to seize an end finding coil thereon, a stationary supporting member, a sleeve mounted on said member for axial and rotary movement, means on said sleeve supporting said finder in laterally offset relation thereto, power driven means for reciprocating said sleeve to move the finder into and out of engagement with a bobbin in the delivery position, and cam means operative as an incident to the movement of the sleeve in the withdrawing movement of the finder to impart a rotary movement to the sleeve and a lateral shifting movement to the finder.
